RATCHET DRILL.

No. 462,543.

Patented Nov. 3, 1891.

UNITED STATES PATENT OFFICE.

GEORGE L. EVATT, OF PORT HOPE, CANADA.

RATCHET-DRILL.

SPECIFICATION forming part of Letters Patent No. 462,543, dated November 3, 1891.

Application filed October 15, 1890. Serial No. 368,180. (No model.)

To all whom it may concern:

Be it known that I, GEORGE L. EVATT, of Port Hope, Province of Ontario, Dominion of Canada, have invented a new and Improved Ratchet-Drill, of which the following is a full, clear, and exact description.

The object of the invention is to provide a new and improved ratchet-drill which is simple and durable in construction, very effective in operation, and adapted to drive the bit continuously forward on both the forward and backward strokes of the handle.

The invention consists in certain parts and details and combinations of the same, as will be described hereinafter and then pointed out in the claims.

Reference is to be had to the accompanying drawings, forming a part of this specification, in which similar letters of reference indicate corresponding parts in all the figures.

Figure 1 is a side elevation of the improvement. Fig. 2 is a sectional side elevation of the same. Fig. 3 is a sectional plan view of part of the improvement on the line *x-x* of Fig. 1. Fig. 4 is a sectional plan view of the improvement on the line *y-y* of Fig. 2. Fig. 5 is an inverted plan view of one of the ratchet mechanisms. Fig. 6 is an enlarged sectional plan view of the improvement on the line *z-z* of Fig. 2. Fig. 7 is an enlarged side elevation of the stock. Fig. 8 is an enlarged sectional plan view of part of the improvement on the line *w-w* of Fig. 1, and Fig. 9 is a similar view of part of the improvement on the line *v-v* of Fig. 2.

The improved ratchet-drill is provided with a stock A, in the lower end of which is adapted to be held the bit B. The stock A is provided with a shank C, mounted to turn in a hub D', formed centrally in the bottom of the casing D, in or through which the said shank C extends centrally. On the lower end of the shank C is formed a collar C', abutting against the under side of the hub D', and on the said shank are also formed the two ratchet-wheels C² and C³, Fig. 7, and a reduced end C⁴, provided with an annular groove C⁵ and extending through the cover F, held on top of the casing D. The latter is provided on its outside with a horizontally-extending handle E, taken hold of by the operator to work the ratchet-drill, as hereinafter more fully de-

scribed. The upper end of the stock A also extends into a central hub F', formed on top of the cover F and provided at its outer end with threads or a fixed nut G, in which screws the feed-screw H, provided on its outer end with a triangularly-shaped head H', adapted to abut against the fixed part located opposite the part to be drilled by the bit B.

On the hub F' is mounted to turn loosely the horizontally-extending handle I, carrying the spring-pressed pawl I', engaging a ratchet-wheel J, secured or formed on the hub F', and serving to turn the said hub and its cover F, so as to screw up the feed-screw H when feeding the device.

The lower ratchet-wheel C² of the shank C is engaged by a pawl E', Fig. 8, pressed on by a spring E² and pivoted in the handle E of the casing D. The next ratchet-wheel C³ of the shank C is engaged by one, two, or more spring-pressed pawls K', pivoted in the lower face of a gear-wheel K, mounted to turn loosely on the shank C. The gear-wheel K is in mesh with a number of pinions L, Fig. 2, journaled in an annular flange F², Fig. 6, projecting from the bottom of the cover F into the casing D. Each of the pinions L carries a larger gear-wheel N in mesh with an internal gear-wheel O, formed on the inside of the casing D.

In order to lock the cover F, the casing D, and the stock A together, blocks P are employed, which pass through recesses in the hub F' into the annular groove C⁵, formed in the upper reduced part C⁴ of the shank C of the stock A. Each of the blocks P is provided with an outwardly-projecting pin P', engaged by an L-shaped slot Q', formed on a ring Q, adapted to slip over the hub F' of the cover to prevent the said blocks from becoming disengaged from the hub F'.

The operation is as follows: When the several parts are in position, as illustrated in Figs. 1 and 2, the operator takes hold of the handle I with his left hand and with his right hand moves the handle E backward and forward. At the forward movement of the handle E in the direction of the arrow a', (see Fig. 6,) the spring-pressed pawl E', by engaging a tooth of the ratchet-wheel C², turns the stock A and the bit B in the direction of the arrow a'. On the backward movement of the

handle E the spring-pressed pawl E' glides over the teeth of the ratchet-wheel C², and at the same time the internal gear-wheel O turns the gear-wheels N, which thus impart a similar movement to the pinions L, and the latter, engaging the gear-wheel K, turns the latter in the direction of the arrow a'. This movement of the gear-wheel K causes a like movement of the stock A as the pawls K' of the said gear-wheel engage the ratchet-wheel C³ of the stock A and its bit B. Thus on the forward as well as on the backward stroke of the handle E a forward movement is imparted to the bit B, it being understood that on the forward movement of said handle the gear-wheels N and L roll off on their respective gear-wheels O and K, the pawls K' sliding back on the ratchet C³.

It is not necessary to hold either handle stationary at any time. The only care required is that the handle I must be moved from the operator while E is being drawn toward him. The working of the drill is not interfered with at any time, but continues uninterruptedly until the desired work is accomplished.

Having thus described my invention, I claim as new and desire to secure by Letters Patent—

30 1. In a ratchet-drill, the combination, with a stock adapted to carry the bit and provided with two ratchet-wheels, of a handled casing in which is pivoted to turn the said stock and which is connected by a spring-pressed pawl with one of said ratchet-wheels, and a gear-wheel carrying spring-pressed pawls engaging the said second ratchet-wheel, the said gear-wheel being connected by differential gear-wheels with the handled casing, substantially as shown and described.

2. In a ratchet-drill, the combination, with a stock adapted to carry the bit and provided with two ratchet-wheels, of a handled casing provided with an internal annular gear-wheel, a gear-wheel mounted to turn loosely on the said stock within the said casing, spring-pressed pawls held in the said gear-wheel and adapted to engage one of said ratchet-wheels on the stock, and differential gear-wheels connecting the said gear-wheel with the internal annular gear-wheel on the said casing, substantially as shown and described.

3. In a ratchet-drill, the combination, with a stock adapted to carry the bit and provided with two ratchet-wheels, of a handled casing provided with an internal annular gear-wheel, a gear-wheel mounted to turn loosely on the said stock within the said casing, spring-pressed pawls held in the said gear-wheel and adapted to engage one of said ratchet-wheels on the stock, differential gear-wheels connecting the said gear-wheel with the internal annular gear-wheel on the said casing, and a spring-pressed pawl held on the said handled casing and engaging with the other of the said ratchet-wheels on the stock, substantially as shown and described.

4. In a ratchet-drill, the combination, with a stock adapted to carry the bit and provided with two ratchet-wheels, of a handled casing provided with an internal annular gear-wheel, and a pawl engaging one of said ratchet-wheels, a cover adapted to be held in a fixed position on top of the said casing, differential gear-wheels mounted to turn in the said cover, and a central gear-wheel mounted to turn loosely on the said stock and in mesh with the said differential gear-wheels, and also provided with spring-pressed pawls engaging with the other ratchet-wheel on the stock, substantially as shown and described.

5. In a ratchet-drill, the combination, with a stock adapted to carry the bit and provided with two ratchet-wheels, of a handled casing provided with an internal annular gear-wheel, and a pawl engaging one of said ratchet-wheels, a cover adapted to be held in a fixed position on top of the said casing, differential gear-wheels mounted to turn in the said cover, a central gear-wheel mounted to turn loosely on the said stock and in mesh with the said differential gear-wheels, and also provided with spring-pressed pawls engaging with the other ratchet-wheel on the stock, a feed-screw screwing in the said cover, and means, substantially as described, for turning the said cover, as set forth.

6. In a ratchet-drill, the combination, with a stock adapted to carry the bit and provided with two ratchet-wheels, of a handled casing provided with an internal annular gear-wheel, and a pawl engaging one of said ratchet-wheels, a cover adapted to be held in a fixed position on top of the said casing, differential gear-wheels mounted to turn in the said cover, a central gear-wheel mounted to turn loosely on the said stock and in mesh with the said differential gear-wheels, and also provided with spring-pressed pawls engaging with the other ratchet-wheel on the stock, and means, substantially as described, for locking the said cover to the said stock and the said casing, substantially as shown and described.

7. The combination, with the handle-casing, the rotary stock mounted therein, extending at its upper end through the top of the casing and provided with an annular groove C⁵, of the central hub F, into the lower end of which the said grooved end of the socket projects, the blocks P, extending through recesses in the hub into the said groove C⁵ and provided on their outer ends with the pins P', the ring Q on the hub, provided with angle slots, into which said pins project, the feed-screw extending through the upper threaded end of the hub, the ratchet-wheel on the hub, and a handle I, having a pawl engaging the said ratchet, substantially as set forth.
